United States Patent Office.

JOSEPH DILLIER, OF GREENSBURG, INDIANA.

Letters Patent No. 101,836, dated April 12, 1870.

IMPROVEMENT IN WHEAT-DRILLS.

The Schedule referred to in these Letters Patent and making part of the same

To all whom it may concern:

Be it known that I, JOSEPH DILLIER, of Greensburg, in the county of Decatur and State of Indiana, have invented certain new and useful Improvements in Wheat-Drills; and I do hereby declare that the following is a full, clear, and exact description thereof, reference being had to the accompanying drawings and to the letters of reference marked thereon, which form a part of this specification, in which—

Figure 1 represents a side elevation of my drill.

Figure 2 is a rear view of the same.

The nature of my invention consists in the construction of a wheat-drill with a gutta-percha screw in the seed-box, in connection with other devices hereinafter described.

A, in the annexed drawings, represents the frame of my machine, which is formed with the two extension bars b b', (see fig. 2.)

To each side of frame A is hinged a beam, C.

d d represent the standards, two of which are attached to each of beams C.

The said standards are made concave on the rear side, and each furnished with a shovel, s, for opening the soil.

To give adequate strength to the standards they are braced with rods t.

In addition to the four standards described, a fifth, of similar construction, is secured to the bottom frame A a little in advance of the front standards on beams C.

E designates a driving-wheel, the axle of which is pivoted on hangers m m, the said hangers being let into bars b b, and bolted at top to handles F.

On the same axle with wheel E is hung the bevel-pinion h.

g is a vertical shaft, the upper end of which is pivoted in the bottom of seed-box H.

The shaft g is kept in position by means of a metal loop I fastened to b.

On the lower end of shaft g is hung the bevel-pinion n, which gears into wheel h.

The top of shaft is also furnished with a bevel-wheel e, the use of which will be hereafter explained.

Directly above the shaft g is placed the seed-box H, the rear edge of which rests on handles F, and having its ends supported by the iron stays L L.

k designates a gutta-percha screw extending lengthwise of seed-box H, and pivoted in the ends of said box.

The screw k is partly sunk in a depression made in the bottom of box H, and is furnished with a bevel-wheel, j, which gears into wheel e on shaft g.

Through the bottom of seed-box are five perforations through which the grain is allowed to pass into a corresponding number of funnel-shaped tubes P.

The lower ends of said tubes enter holes in beams C, and into standards d, and thence into the furrow.

R represents an iron rod bent at right angles at top, and passing downward through bar T and slide G and then fastened to the center of double lever u.

Slide G is slightly curved in shape, and its ends rest loosely in metal loops at the bottom of the hinged beams C.

To each end of lever u a metal rod, o, is hooked, the opposite ends of said rods being fastened to their respective beams C.

It will be observed that by operating rod R, the beams C and the shovels attached to them can be moved inward or outward at pleasure.

W represents a wheel hung near the front end of frame A, in order to keep said frame on a level.

It will be seen that in order to drive the grain toward the center of the seed-box, the thread of the screw is reversed from the left end to the nearest hole through which the grain is discharged.

It will also be observed that tubes P are inserted at their lower ends into shorter tubes which enter the perforations in beams C, while their upper ends are pivoted to the bottom of the seed-box. By this arrangement tubes P can adapt themselves to the outward or inward motion of beam C.

In operating my machine the driving-wheel revolves the shaft g and pinions n and e on said shaft, and that pinion being made to gear into bevel-wheel j on screw k, the seed is distributed by said screw.

Having thus described my invention, what I claim, and desire to secure by Letters Patent, is—

1. The gutta-percha screw k for distributing the seed, in the manner set forth.

2. The combination of screw k and wheel j with shaft g, furnished with pinions n and e, the whole arranged and operated in the manner and for the purpose substantially as specified.

3. The combination of seed-box H, furnished with screw k, wheel j, shaft g, pinions e and n, tubes P slide G, hinged beams C, and standards d, the whole constructed and arranged substantially as set forth.

In testimony that I claim the forgoing as my own, I affix my signature in presence of two witnesses.

JOSEPH DILLIER. [t. s.]
